UNITED STATES PATENT OFFICE.

EMMIT G. LATTA, OF SYRACUSE, NEW YORK, ASSIGNOR TO CORONA TYPEWRITER COMPANY, INC., A CORPORATION OF NEW YORK.

TYPE-WRITING MACHINE.

1,274,566.

Specification of Letters Patent.

Patented Aug. 6, 1918.

Application filed December 4, 1915. Serial No. 64,950.

To all whom it may concern:

Be it known that I, EMMIT G. LATTA, a citizen of the United States, residing at Syracuse, in the county of Onondaga and State of New York, have invented a new and useful Improvement in Type-Writing Machines, of which the following is a specification.

This invention relates to improvements in portable typewriting machines of the kind which are adapted to be collapsed for reducing their dimensions so as to facilitate carrying the same from place to place.

The objects of the invention are to produce a complete typewriting machine of the front strike type-bar kind which can be collapsed to occupy less space when not in use than any known type-bar machine; also to produce a typewriter in which the keyboard occupies a position very close to the type bars and very low down when the machine is collapsed; also to mount the keyboard on the movable part of the collapsible frame in such a way that the movement of said frame up and down to and from its operative position does not disturb the relation of the keyboard to the frame and other coöperating parts of the machine, such as the type-bar actions and case shifting mechanism; also to mount the type-bars on a pivoted shift frame which is pivotally mounted in such relation to the key actions and pivot connecting the parts of the collapsible main frame that the type-bars will have the same action in all positions of the shift frame and will not be affected by the collapsing of the machine; also to so arrange the universal bar and its connections with the parts actuated thereby, that these parts will retain their connections when the machine is collapsed; and also to improve typewriting machines in the other respects hereinafter described and claimed.

In the accompanying drawings:

Figure 1 is a longitudinal sectional elevation of a typewriting machine embodying the invention, parts of the machine being omitted to simplify the drawing.

Figs. 2 and 3 are fragmentary longitudinal sectional elevations on line 2-2, Fig. 4, respectively, showing the space bar in the normal and depressed positions.

Fig. 4 is a fragmentary plan view, partly

in section, of the machine, portions of the movable frame and carriage being omitted to disclose the underlying parts.

Fig. 5 is a side elevation of the frame of the machine, one side of the movable frame being partially broken away.

Fig. 6 is a transverse sectional elevation of the machine in line 6-6, Fig. 1.

Fig. 7 is a longitudinal sectional elevation similar to Fig. 1, showing the machine collapsed.

Fig. 8 is a fragmentary longitudinal sectional elevation showing the position of one of the type bars, the universal bar and connected parts when one of the finger keys is depressed.

Fig. 9 is a fragmentary side elevation of the front portion of the movable frame with the side plate thereof removed.

This invention is in the nature of an improvement on the machine disclosed in my pending application, Serial No. 658,153, filed Nov. 2nd, 1911, and most of the parts omitted from the drawings hereof to simplify the same can be the same as the corresponding parts shown in said application.

The main frame of the machine, as in said other machine, is composed of a stationary base frame or part A adapted to rest on a supporting surface, and a movable frame or part B, which is pivoted at its front portion to the front portion of the stationary frame so that the rear portion of the movable frame, which supports the platen carriage can swing to lower the carriage from an elevated operative position to an inoperative position in rear of the type-bars, which are mounted in the stationary frame, but the pivotal connection of the frames is located higher and farther to the rear than in said other machine in order to further reduce both the height and length of the machine when collapsed and the frames are of somewhat different construction for the purpose hereinafter described. The stationary frame A has sides a which are disconnected at their front ends to leave the space between them unobstructed, and the front end or cross bar b of the movable frame is detachably secured to the sides b' thereof, by screws b² or otherwise, to facilitate machining the cross-bar which constitutes the fulcrum support for the key actions and other parts.

The frames are pivotally connected preferably by screws C which are screwed tightly into threaded holes in the sides of the stationary frame and have large heads fitting 5 in circular holes in the sides of the movable frame, which are located outside of the sides of the stationary frame. The movable frame can be stationarily secured in its raised and lowered positions to the stationary 10 frame by any suitable means, such as thumb screws c carried by the sides of the movable frame and adapted to be screwed into upper or lower holes c' c" in the sides of the stationary frame, as in said other machine.

D represents the platen which is journaled in a carriage which can be constructed and arranged to travel crosswise of the machine on a guide track d on the rear end of the 20 movable frame B, as disclosed in said application or in any other suitable manner.

E represents one of the type-bars which are pivotally mounted in any suitable way on a supporting segment e so as to swing 25 upwardly and rearwardly to print at the front side of the platen. Each type-bar has a plurality of type, preferably three, and the segment is secured on a shift frame F which is pivoted in the stationary frame 30 A to swing up and down for printing different case characters. The shift frame is pivoted to swing about an axis coincident or substantially coincident with the pivoted axis of the movable main frame B, the shift frame 35 preferably having forwardly diverging arms pivoted on the reduced inner ends of the pivot screws C for the main frame. The shift frame and the movable main frame B can, however, be pivoted in any other suitable way enabling them to swing about a common or substantially common center.

f f' represent shift keys such as shown in said application provided with cam portions engaging a roller f² on the shift frame for 40 shifting the shift frame up and down. f' represents a cross rod which rigidly connects the sides of the shift frame and serves to support the type basket or back stop f" for the type-bars.

G represents the finger keys for actuating the type-bars. They are provided with key stems g g' g" of as many different forms as there are banks of keys, there being in the construction shown, three banks of keys and 50 three different forms of stems. Each key stem is pivoted to a pair of parallel supporting links h h' which are pivoted to and extend rearwardly, one above the other from the front cross-bar b of the movable frame 55 B. The lower portions of all of the key stems, which are pivoted to the links are arranged side by side in a single transverse row or plane, and the upper portions of the key stems g extend substantially directly upwardly from their connections with the links

h while the upper portions of the stems g' extend forwardly and upwardly and the upper portions of the remaining stems g" extend rearwardly and upwardly from their connections with the links h, thus locating 70 the finger keys in three transverse banks or rows, one in front and one in the rear of the middle bank or row of keys on the straight key stems g. Preferably the upper links h enter vertical slots h² in a rearwardly projecting upper edge of the cross-bar and are pivoted on a single pivot wire h³ while the lower link h' are similarly pivoted in slots in the lower edge of the bar on a second pivot wire h⁴. Each slotted edge of the bar b is 80 cut lengthwise at h⁵ intersecting the slots, see Fig. 6 and the bottom of this cut is planed out to form a seat for the pivot wire and prevent its lateral displacement. The pivot wires h³ h⁴ extend from end to end of 85 the cross-bar and are held from longitudinal movement by the sides of the frame B. In this way the links for the whole series of keys are pivoted on two pivot wires, which greatly simplifies the manufacture, while, 90 nevertheless, providing strong stable pivotal connections affording ample lateral support for the links.

I represents connecting links pivoted at their front ends to depending legs i on the 95 upper key supporting links h and pivoted at their rear ends to the type-bars. All of the pivot joints between the connecting links I and the key supporting links h are located on a single line i' coincident or substantially 100 coincident with the pivotal axis of the frame B and the shift frame F. This arrangement insures the same action of the keys and type-bars in all positions of the shift frame, and when the machine is collapsed the finger keys 105 and their supporting stems and links can swing with the frame B about the line i' from their operative position to the collapsed position shown in Fig. 7, from which it will be seen that the high rear portion of keyboard moves downwardly and rearwardly 110 toward the type-bars while the front portion thereof and the front end of the movable frame B move upwardly and rearwardly thereby decreasing both the height and 115 length of the machine from front to rear.

K represents the universal bar, which is preferably suspended by upright end legs k and a middle leg k' entering slots in the upper edge of the cross-bar b and pivoted on 120 the pivot wire h⁵ in the same manner as the upper key supporting links h. The universal bar is located in front of, and is adapted to be struck and moved forwardly by the legs i of the upper key supporting links 125 h when the keys are depressed, as shown in Fig. 8. The middle leg k' of the universal bar is pivoted to the front end of a rod or link L which passes rearwardly and upwardly between the two central type-bars 130

and is pivoted at its rear end to a combined ribbon vibrator and escapement trip lever l fulcrumed on the rear end of the movable frame B beneath the carriage. The front 5 end of this lever l is connected to a ribbon vibrator l' which may be of any suitable construction and its rear end is connected as by a rod l^2 , to the carriage escapement (not shown) for actuating these devices. As 10 both ends of the rod L and the parts to which it is connected are supported by the movable frame B, it is not necessary for the pivot joint between the rod L and the universal bar to be on the pivot line i for the 15 frame B, as in the case of the joints connecting the type-bar links I to the key-supporting links h . The rod L is arched where it passes over the type-bar segment so as not to strike the latter when the machine is collapsed. 20

M represents the space-bar which, as shown, is provided with end arms m and a middle arm m' which like the arms of the universal bar are fulcrumed on the pivot 25 wire h^3 in vertical slots in the upper edge of the cross-bar b . The middle arm m' is connected by a link m^2 , Figs. 2 and 3 to a lever n which is preferably fulcrumed on the lower pivot wire h^4 in a slot in the lower 30 edge of the cross-bar with one end arranged to strike a projection n' on the universal bar for moving the latter when the space bar is depressed. The lever n and link m^2 are omitted from Fig. 1 to avoid complicating 35 this figure. As the slots in the cross-bar b for the several key-supporting links, and arms for the universal bar and space bar can all be cut at the same time by a series of suitable cutters arranged on a single 40 mandrel, the cross bar is inexpensive to make.

The upright parts of several of the key stems at the middle of the keyboard are offset slightly between the pivots connecting them 45 to the upper and lower links h h' , as indicated at ϕ in Fig. 4, in order to clear the links I. The remaining key stems are not offset in this way, as the diverging lines of the links I connected to them makes this 50 unnecessary. The key stems, as seen in Fig. 4, are located at the outer sides of the links h except in the case of one of the stems adjacent to the bar L which is located at the inner side of the link to make room for 55 the slots in the bar b which receive the middle arms, h h' and for the universal bar and space bar. The key actions and other working parts of the machine are returned to their normal positions by suitable springs 60 which are not shown in order not to confuse the drawings. Springs which partially support the weight of the shift frame are also omitted for the same reason.

By a comparison of Figs. 1 and 7, it will 65 be seen that the front end of the movable

frame B, together with the space bar M and the low front bank of keys G swing upwardly and rearwardly while the other two banks of keys swing rearwardly and downwardly when the machine is collapsed. 70 This materially shortens the machine from front to rear and reduces the height of its front end. As seen in Fig. 7, the rear bank of keys lie close to the front ends of the type-bars and all of the keys lie below the 75 elevation of the highest part of the stationary frame when the machine is collapsed, whereas some of the keys project to a higher elevation when in their operative position.

No claims are made in the application for 80 certain of the features shown, such as the key actions, the arrangement of the universal bar, and the pivotal mountings for these parts and the space bar, as these features are claimed in another application. 85

I claim as my invention:—

1. In a collapsible typewriting machine having a keyboard, a main frame which supports the working parts of the machine and is composed of two frame parts pivotally 90 connected at a point in the rear of and below the front portion of the keyboard so that the front part of the keyboard moves rearwardly when the movable part of the frame is swung on its pivot to collapse the machine. 95

2. In a collapsible typewriting machine having a keyboard with keys arranged at different elevations, a main frame which supports the working parts of the machine and is composed of two frame parts pivotally 100 connected at a point in front of and below the rear part of the keyboard so that the highest part of the keyboard moves downwardly when the movable part of the frame is swung on its pivot to collapse the 105 machine.

3. In a collapsible typewriting machine having a keyboard with keys arranged at different elevations, a main frame which supports the working parts of the machine 110 and is composed of two frame parts pivotally connected at a point between the front and rear portions of the keyboard and below the rear portion thereof so that the front part of the keyboard moves rearwardly and 115 the highest part of the keyboard moves downwardly when the movable part of the frame is swung on its pivot to collapse the machine.

4. In a collapsible typewriting machine, 120 the combination of a main frame comprising two parts which are pivotally connected near their front ends for collapsing the machine, one of said parts being movable, finger keys and a platen supported by one 125 of said frame parts, and key-actuated printing instrumentalities supported by the other frame part, said platen being supported by the rear portion of said movable frame part in position to be lowered from an elevated 130

operative position to a position in rear of said printing instrumentality when the machine is collapsed.

5. In a collapsible typewriting machine, 5 the combination of a main frame comprising two parts which are pivotally connected near their front ends for collapsing the machine, printing instrumentalities supported by one of said frame parts, finger keys and 10 a platen supported by said other frame part respectively at the front and rear portions thereof in position to move when the machine is collapsed from operative positions to lower inoperative positions in front and 15 in rear of the printing instrumentalities.

6. In a collapsible typewriting machine, the combination of a stationary frame, a frame movably mounted on said stationary frame to move toward the same for collapsing 20 the machine, printing instrumentalities supported by said stationary frame, and finger keys and a platen arranged respectively in front and in rear of said printing instrumentalities to move with said movable 25 frame from their operative positions to different positions respectively in front and in rear of said printing instrumentalities.

7. In a collapsible typewriting machine, the combination of a stationary frame, a 30 frame movably mounted on said stationary frame to move toward the same for collapsing the machine, printing instrumentalities supported by said stationary frame, and finger keys and a platen supported by said movable frame and movable therewith from 35 their operative positions to inoperative positions respectively in front and in rear of said printing instrumentalities.

8. In a collapsible typewriting machine, 40 the combination of a stationary frame, a frame mounted on said stationary frame to move relative thereto for collapsing the machine, printing instrumentalities supported by said stationary frame, and finger keys 45 and a platen supported by and movable with said movable frame part from their operative positions to inoperative positions for collapsing the machine.

9. In a collapsible typewriting machine, 50 the combination of a main frame comprising two normally stationary parts one of which is movable relative to the other for collapsing the machine, a platen and finger keys supported by one of said frame parts, a 55 series of type bars each having a plurality of type supported by the other frame part, and means for shifting said type bars to different case printing positions.

10. In a collapsible typewriting machine, 60 the combination of a main frame comprising two normally stationary parts one of which is movable relative to the other for collapsing the machine, a platen and finger keys supported by one of said frame parts in 65 fixed relation to each other, a series of type

bars each having a plurality of type supported by said other frame part, and means for changing the relation between the platen and type bars for printing different case characters without moving said movable 70 frame part.

11. In a collapsible typewriting machine, the combination of a collapsible main frame comprising two pivotally connected frame parts, a platen supported by one of said 75 frame parts, type-bars, and a shift frame for said type-bars, said shift frame being pivotally mounted to swing about an axis substantially coincident with the pivotal axis of said frame parts. 80

12. In a collapsible typewriting machine, the combination of a collapsible main frame comprising two pivotally connected frame parts, type bars supported by one of said frame parts, and finger keys for operating 85 said type bars supported by the other frame part to swing therewith about an axis substantially coincident with the pivotal axis of said frame parts.

13. In a collapsible typewriting machine, 90 the combination of a collapsible main frame comprising two pivotally connected frame parts, type bars supported by one of said frame parts, finger keys supported by said other frame part, and operating connections 95 between said finger keys and type-bars, including pivot joints arranged substantially in line with the pivotal axis of said frame parts.

14. In a collapsible typewriting machine, 100 the combination of a collapsible main frame comprising two pivotally connected frame parts, type-bars supported by one of said frame parts, finger keys supported by said other frame part and arranged in different 105 positions one in front of the other, operating connections between each of said finger keys and one of said type-bars including a pivot joint, said pivot joints for all of said keys being arranged substantially in line with the 110 pivotal axis of said frame parts. 105

15. In a collapsible typewriting machine, the combination of a collapsible main frame comprising two pivotally connected frame parts, type-bars supported by one of said 115 frame parts, a series of key-actuated links supported by said other frame part, links pivoted to said key-actuated links and to the type-bars, the pivot joints between said links being located substantially in line with the 120 pivotal axis of said frame parts.

16. In a collapsible typewriting machine, the combination of a collapsible main frame comprising two pivotally connected frame parts, type-bars supported by one of said 125 frame parts, finger keys for actuating said type-bars, supporting links for said finger keys fulcrumed on said other frame part, and links pivoted to said supporting links and to said type-bars, the pivot joints be- 130

tween said links being located substantially in line with the pivotal axis of said frame parts.

17. In a collapsible typewriting machine, the combination of a collapsible main frame comprising two pivotally connected parts one of which is movable for collapsing the machine, a series of type-bars each having a plurality of type, a pivoted shift frame for said type bars, finger keys movable with said movable frame part, operating connections between said finger keys and said type bars including pivot joints, the said pivot joints and the pivot for said shift frame being located substantially in line with the pivotal axis of said frame parts.

18. In a typewriting machine, the combination of a main frame, a series of type-bars each having a plurality of type, a shift frame for the type bars pivoted to said main frame, a series of key-actuated links, and links pivoted to said key-actuated links and to the type-bars, the pivot joints between said links being located substantially in line with the pivotal axis of said shift frame.

19. In a collapsible typewriting machine, the combination of a collapsible main frame comprising two pivotally connected frame parts one of which is movable for collapsing the machine, a series of type bars each provided with a plurality of type, a pivoted shift frame for said type bars, a series of key-actuated links supported by the movable frame part, and links pivoted to said key-actuated links and to the type bars, the pivot joints between said links and the pivots for said frame parts and for said shift frame being located substantially in line.

20. In a collapsible typewriting machine, the combination of a stationary frame, a frame pivotally connected to said stationary frame to swing relative to the same for collapsing the machine, type-bars supported by said stationary frame, and a keyboard comprising finger keys which swing with said pivoted frame when the latter is swung for collapsing the machine, the pivotal axis of said pivotal frame being located forward of and below the rear edge of the keyboard so that the finger keys at the rear portion of the keyboard are lowered when the machine is collapsed.

21. In a typewriting machine, the combination of a stationary frame, a frame mounted on said stationary frame to move toward the same for collapsing the machine, type-bars and key actions therefor, a universal bar which is actuated by said key actions, a device to be actuated by said universal bar and means connecting said universal bar and device, said universal bar, device and connecting means being all supported by and movable with said movable frame.

22. In a typewriting machine, the combination of a stationary frame, a frame

mounted on said stationary frame to move toward the same for collapsing the machine, type-bars and key actions therefor, a universal bar mounted on the front portion of said movable frame in position to be actuated by said key actions, a device mounted on the rear portion of the movable frame, and a rod connecting the universal bar and said device, said universal bar, device and rod all being movable with said movable frame.

23. In a typewriting machine, the combination of a stationary frame, a frame mounted on said stationary frame to move toward the same for collapsing the machine, type bars supported by said stationary frame, key actions supported by said movable frame and connected to said type bars, a universal bar supported on said movable frame in position to be actuated by said key actions, a device supported on the movable frame, and a rod connecting the universal bar and said device for actuating the latter, said key actions, universal bar, device and rod all being movable with said movable frame.

24. In a typewriting machine, the combination of a stationary frame, a frame mounted on said stationary frame to move toward the same for collapsing the machine, type-bars, key actions for said type-bars mounted on the front portion of said movable frame, a universal bar mounted on said movable frame in front of said key actions in position to be actuated thereby, a device mounted on the movable frame, and a rod connecting said universal bar and said device for actuating the latter, said key actions, universal bar, device and rod all being movable with said movable frame.

25. In a typewriting machine, the combination of a stationary frame, a frame mounted on said stationary frame to move toward the same for collapsing the machine, type-bars, key actions mounted on the front portion of said movable frame and connected to said type-bars, a universal bar mounted on the front portion of said movable frame in position to be actuated by the key actions, a space bar mounted on the front portion of the movable frame and connections for actuating said universal bar, a device mounted on the movable frame, and a rod connecting the universal bar and said device for actuating the latter, said key actions, universal bar, space bar, device and rod all being movable with the movable frame.

26. In a collapsible typewriting machine, the combination of a main frame comprising two parts, one of which is movable relative to the other for collapsing the machine, a platen and finger keys supported by one of said frame parts, a series of type bars each having a plurality of type supported

by the other frame part, and means for changing the relation between the platen and type bars for printing different case characters without moving said movable frame

5 part.

27. In a collapsible typewriting machine, the combination of a main frame comprising two parts, one of which is movable relative to the other for collapsing the machine, 10 a platen and finger keys supported by one of said frame parts, a series of type bars each having a plurality of type supported by the other frame part, means for changing the relation between the platen and type 15 bars for printing different case characters without moving said movable frame part, and means for maintaining a positive permanent connection between the key levers and the type bars in both the operative and 20 inoperative positions of the main frame parts.

28. In a collapsible typewriting machine, the combination of a main frame comprising two normally stationary parts one of 25 which is movable relative to the other for collapsing the machine, a platen and finger keys supported by one of said frame parts, a series of type bars each having a plurality of type supported by the other frame part, 30 means for shifting said type bars to different case printing positions, and means for maintaining a positive permanent connection between the key levers and the type bars in both the operative and inoperative positions 35 of the main frame parts.

29. In a collapsible typewriting machine, the combination of a main frame comprising two parts, one of which is movable relative to the other for collapsing the machine, a 40 platen, finger keys and universal bar supported by one of said frame parts, a series of type bars supported by the other frame part, and means forming permanent positive connections between the type bars and 45 universal bar and the actuating keys at all times when the machine is in its collapsed inoperative position and in its extended operative position.

30. In a typewriting machine, the combination of a frame comprising two pivotally connected members one of which is movable for collapsing the machine, a platen carriage supported on the movable frame member, type bars supported in the other frame 55 member, rows of parallel links pivoted at their forward ends in the movable frame member, a series of key-stems arranged in a single row and movably supported by the free rear ends of said links, finger keys arranged in banks and supported on said key 60 stems, and permanent foldable connections between the type bars and the links forming one of said rows.

31. In a typewriting machine, the combination of a frame comprising two mem-

bers pivotally connected together intermediate their ends and one of which is movable for collapsing the machine, a platen carriage supported on the movable frame member at the rear end thereof, parallel 70 rows of links arranged one above the other, the links of each row being pivotally supported at their forward ends in the front end of the movable frame, a series of key stems having upright portions arranged in a single row and pivotally connected with the free rear ends of the links of each row, finger keys supported on the key stems and arranged in banks by extending the key stems upwardly in different directions from 75 the upright portions thereof, type bars supported in the stationary frame member, and foldable means forming a positive connection between the links and type bars in both the operative and collapsed positions of the 80 frame members, the point of fold of said means being coincident with the pivotal point of the frame members.

32. In a typewriting machine, the combination of a frame comprising two members pivotally connected together intermediate their ends and one of which is movable for collapsing the machine, a platen carriage supported at the rear of the movable frame member, type bars supported in the other frame member, parallel rows of links arranged one above the other, the links of each row being pivotally supported at their forward ends in the forward end of the movable frame member, a series of key 90 stems supporting keys in banks and each of said key stems being pivoted to the rear end of one link of each row, depending arms rigidly connected with the links of one row, a universal bar movably supported at the 95 front end of the movable frame member and adapted to be moved by said depending arms, and links pivotally connected to said arms and type bars, the pivot joints between the links and arms being in alinement with 100 the pivotal point of the frame.

33. In a typewriting machine, the combination of a frame comprising a stationary member and a member supported by the stationary member and movable toward the same for collapsing the machine, a platen carriage supported at the rear of said movable member, type bars supported in the stationary member, key-operated levers supported at the front of said movable member 115 and operatively connected with the type bars, a universal bar supported at the front of said movable member in position to be actuated by said key-operated levers, a combined ribbon vibrator and carriage escapement actuating device supported on the movable frame member, and an operative connection between the universal bar and said device.

34. In a typewriting machine, the com-

130

- bination of a frame comprising a stationary member and a member supported by the stationary member and movable toward the same for collapsing the machine, a platen carriage supported at the rear of said movable member, type bars supported in the stationary member, key-operated levers supported at the front of said movable member and operatively connected with the type bars, a universal bar supported at the front of said movable member in position to be actuated by said key-operated levers, a bell-crank lever supported in the rear end of the movable frame member and having one arm operatively connected with a ribbon vibrator, and a link connecting the universal bar with an arm of said lever to rock the lever.
35. In a typewriting machine, the combination of a frame comprising a stationary member and a member supported by the stationary member and movable toward the same for collapsing the machine, a platen carriage supported at the rear of said movable member, type bars supported in the stationary member, key-operated levers supported at the front of said movable member and operatively connected with the type bars, a universal bar supported at the front of said movable member in position to be actuated by said key-operated levers, a bell-crank lever supported in the rear end of the movable frame member and having one arm connected with a carriage-escapement-actuating device, and a link connecting the universal bar and the lever to rock said lever.
36. In a collapsible typewriting machine, the combination of a base frame, type bars mounted on the base frame, a key action having constantly maintained operating connections with the type bars, a universal bar supported in position to be actuated by the key action, a platen carriage, escapement actuating means having a constantly maintained operating connection with the universal bar, and means held to the base frame part adapted to support the carriage and escapement actuating means in a normal elevated operative position with relation to the type bars, said supporting means being movable to shift the carriage while upright to a materially lower inoperative position at the rear of the type bars.
37. In a collapsible typewriting machine, the combination of a base frame, type bars mounted on the base frame, a key action having constantly maintained mechanical operating connections with the type bars, a universal bar supported in position to be actuated by the key action, a platen carriage, escapement actuating means and a ribbon vibrator operatively connected with the universal bar and supported in fixed relation to the platen carriage, and means connected

with the base frame forward of the rear end thereof adapted to support the platen carriage in an elevated operative position with relation to the type bars, said supporting means being movable to shift the carriage while substantially upright downwardly to a materially lower inoperative position at the rear of the type bars when the machine is not in use. 70

38. In a collapsible typewriting machine, 75 the combination of a base frame, type bars supported on the base frame, a platen carriage, key-operated levers operatively connected to actuate the type bars, supporting means for the platen carriage and key-operated levers adapted to support the carriage at a higher level than the key-operated levers and type bars when the machine is in use, and connections between said supporting means and the base frame whereby 80 the supporting means may be moved downwardly relatively to the base frame to place the carriage in an upright position at the rear of the key-operated levers and in substantially the same plane as the type bars. 85

39. In a collapsible typewriting machine, the combination of a base frame, type bars supported on the base frame, a platen carriage, key-operated levers adapted to actuate the type bars, and supporting means 95 for the platen carriage and key-operated levers pivotally held to the base frame and movable relatively thereto to shift the platen carriage downwardly while upright from a normal elevated operative position with relation to the type bars to a materially lower position at the rear of the key-operated levers. 100

40. In a collapsible typewriting machine, the combination of a base frame, type bars 105 mounted on the base frame, key-operated levers adapted to actuate the type bars, a platen carriage, a support for the key-operated levers and platen carriage, connections between said support and the base 110 frame whereby said support may be moved to shift the platen carriage while upright from an elevated operative position above the level of the type bars to a materially lower level when the machine is not in use, 115 and means for locking the support against movement to hold the carriage in its elevated operative position.

41. In a collapsible typewriting machine, the combination of a base frame, type bars 120 supported on the base frame, key-operated levers, a platen carriage, supporting means for the platen carriage and key-operated levers held to the base frame and movable relatively thereto to shift the platen carriage 125 downwardly while upright from a normal operative position above the level of the type bars to a materially lower inoperative position at the rear of the type bars and key-operated levers, and constantly 130

maintained mechanical operating connections between the key-operated levers and type bars.

42. In a collapsible typewriting machine, 8 the combination of a base frame, type bars supported on the base frame, key-operated levers, a platen carriage, supporting means for the platen carriage and key-operated levers held to the base frame and movable 10 relatively thereto to shift the platen carriage downwardly while upright from a normal operative position above the level of the type bars to a materially lower inoperative position at the rear of the type bars and key operated levers, constantly maintained mechanical operating connections between the key-operated levers and type bars, and case shift means embodying a shift frame and key-operated levers supported entirely 20 on the base frame and adapted to shift the type bars for printing different case characters.
43. In a collapsible typewriting machine, 25 the combination of a base frame, type bars supported on the base frame, key-operated levers, a universal bar adapted to be actuated by the key-operated levers, a platen carriage, escapement actuating means, means for supporting the key- 30 operated levers and universal bar together with the platen carriage and escapement actuating means to move relatively to

the type-bars from a normal operative position to a more compact inoperative position, constantly maintained operating connections 35 between the key-operated levers and the type bars, and a constantly maintained operating connection between the universal bar and escapement actuating means.

44. In a collapsible typewriting machine, 40 the combination of a base frame, type bars supported on the base frame, key-operated levers, a universal bar adapted to be actuated by the key-operated levers, a platen carriage, escapement actuating means, means 45 for supporting the key-operated levers and universal bar together with the platen carriage and escapement actuating means to move relatively to the type bars from a normal operative position to a more compact 50 inoperative position, constantly maintained operating connections between the key-operated levers and the type bars, a constantly maintained operating connection between the universal bar and escapement actuating 55 means, and means supported entirely on the base frame for shifting the type bars to different case printing positions.

Witness my hand this 29th day of November, 1915.

EMMIT G. LATTA.
